UNITED STATES PATENT OFFICE.

KNUT LUDWIG STENDAHL, OF BRIDGEPORT, CONNECTICUT, ASSIGNOR TO JOHN A. HURLEY, INCORPORATED, OF BRIDGEPORT, CONNECTICUT, A CORPORATION OF CONNECTICUT.

ATTACHMENT FOR EXTINGUISHING OIL-STOVES WHEN OVERTURNED.

1,076,168.

Specification of Letters Patent.

Patented Oct. 21, 1913.

Application filed October 16, 1912. Serial No. 726,184.

To all whom it may concern:

Be it known that I, KNUT LUDWIG STENDAHL, a citizen of the United States, residing at Bridgeport, county of Fairfield, State 5 of Connecticut, have invented an Improvement in Attachments for Extinguishing Oil-Stoves when Overturned, of which the following is a specification.

This invention relates to hydro-carbon 10 stoves of the center draft type and has for its object to provide a simple, inexpensive and dependable attachment therefor that will instantly extinguish a lighted stove should it be overturned.

15 With this end in view I have devised the novel safety extinguishing device of which the following description in connection with the accompanying drawing is a specification, reference characters being used to indicate the several parts.

20 Figure 1 is a view partly in elevation and partly in section illustrating the use of my novel extinguisher in the font of an ordinary oil stove, the parts being in the normal 25 or operative position, and Fig. 2 is an enlarged detail view partly in elevation and partly in section of the extinguishing device detached.

The invention consists in certain details 30 of construction which will be hereinafter described and then specifically pointed out in the claims.

35 10 denotes a font, 11 the draft tube, 12 the wick tube, 13 the wick and 14 the air distributor.

40 15 denotes an extinguisher having a downwardly extending flange 16 which is adapted in the extinguishing position to drop down over the end of the wick and the wick tube. The extinguisher is secured to the air distributor and serves additionally, in the raised position, as a flame spreader. The air distributor and the extinguisher are carried by a vertical rod 17 which extends 45 into a ball chamber 22, perforated to permit free passage of air. Within this chamber is a ball 23 upon which the lower end of the rod rests in the normal position, as shown in Fig. 1. The bottom of the chamber 50 is a concave plate 24 which is provided with perforations to permit free passage of air into the draft tube and with a central hole 25, large enough to be engaged by and to detain the ball without locking it.

The rod is provided with a shoulder 30 55 and a strengthening plate 31 is placed between the shoulder and the air distributor, the parts being secured in place by a ring nut or other hand piece 28. The ball chamber is carried by a frame 32 lying within 60 the draft tube. A wick stop 33 is secured to the upper end of the frame and the lower end of the frame is provided with a threaded rod 34 which extends through a cross piece 35 and is held in place by a ring nut 65 or hand piece 36. The special purpose of this construction is to enable me to raise or lower the wick stop as may be required to produce the desired result by turning the nut.

70 In order to insure the instant fall of the extinguisher and air distributor, should the stove be overturned, I preferably assist gravity by means of a spring 26 one end of which bears against a cross piece 37 in the 75 frame and against a disk 38 or other projection on the rod, and which is shown as inclosed in a sleeve 39 to prevent the possibility of displacement.

75 The operation is as follows: The engagement of the ball with the central hole in the concave plate is sufficient to retain the ball in place and hold the rod, air distributor and flame extinguisher raised under the ordinary conditions of use. Should the 80 stove be overturned, however, the ball will be displaced leaving the rod unsupported and the spring will act to instantly draw the rod downward and with it the extinguisher, which covers the end of the wick 90 and the flange of which extends down below the edge of the wick tube, thereby extinguishing the flame instantly and with practical certainty. When the stove is righted, the operator by means of hand 95 piece 28 raises the rod, air distributor and extinguisher sufficiently to permit the ball to roll to the center of the concave plate and seat itself in the hole and then lowers the rod into engagement with the ball.

100 Having thus described my invention I claim:

1. In an oil stove burner having a cylindrical draft tube, a frame adapted to lie within the draft tube, a closed chamber perforated on all sides and having a concave bottom carried by the frame within the draft tube, a ball therein, an extinguisher

- arm and a rod by which the extinguisher is carried and which normally rests upon the ball.
2. In an oil stove burner having a vertical cylindrical draft tube, a frame adapted to lie within the draft tube, a closed chamber perforated on all sides carried upon the frame within the draft tube and having a bottom consisting of a concave plate with a hole in its center, a ball adapted to engage the hole for the purpose set forth, an extinguisher and a rod by which the extinguisher is carried and which normally rests upon the ball.
- 15 3. In an oil stove burner having a vertical cylindrical draft tube, a frame adapted to lie within the draft tube, a closed chamber perforated on all sides carried thereby within the draft tube and having a concave bottom, a ball resting thereon, an extinguisher, a rod by which the extinguisher is carried and which normally rests upon the ball, and a spring acting to lower the extinguisher when the ball is displaced.
- 20 4. In an oil stove burner having a vertical cylindrical draft tube, a frame adapted to lie within the draft tube, an extinguisher, a spring controlled rod within the draft

tube by which the extinguisher is carried, a ball normally engaged by the rod to retain the extinguisher in the raised position, and a closed chamber perforated on all sides within the draft tube having a concave bottom with a central hole adapted to be engaged by the ball, substantially as described, 35 for the purpose specified.

5. In an oil stove burner having a vertical cylindrical draft tube, a wick tube thereabout, an air distributor and extinguisher, a spring controlled rod within the draft tube by which the air distributor and extinguisher are carried, a ball which is engaged by the rod to normally retain the air distributor and extinguisher in raised position, a closed chamber perforated on all sides within the draft tube having a concave bottom with a hole adapted to be engaged by the ball and a frame within the draft tube by which the chamber is carried.

In testimony whereof I affix my signature in presence of two witnesses.

KNUT LUDWIG STENDAHL.
